BASKET CONSTRUCTION

Arthur Hewson, Grimsby, Ontario, Canada

Application July 25, 1935, Serial No. 33,035

4 Claims. (Cl. 217—123)

This invention relates to improvements in market basket construction and consists essentially of the addition to a standard market basket of a lower inside hoop contiguous to the lower 5 marginal portion of the basket siding, a relatively thin basket bottom marginally supported by the additional hoop, and a metal strap athwart the basket bottom having down turned ears extending over the lateral edges of said bottom and 10 tucked between the siding and inside hoop where they are secured combiningly with the regular outside hoop and the lower end of the bale shafts.

One important object of the invention is to provide means in market basket construction 15 whereby the cost of material is reduced.

Another important object is to provide means of reducing weight in the construction of these baskets.

Another important object is to provide a basket 20 construction whereby while the basket is materially lighter in weight and construction than standard baskets its strength is appreciably increased.

Still another important object is to provide a basket 25 having the foregoing qualities but maintaining the general external appearance of a standard or ordinary market basket.

A fifth important object is to provide a basket 30 having all the foregoing qualities yet the general dimensions prescribed under authority.

With the above and other objects in view as will be hereinafter apparent, the invention consists in general of certain novel details of construction and combinations of parts hereinafter 35 fully described, illustrated in the accompanying drawing and specifically claimed.

In the accompanying drawing like characters of reference indicate like parts in the several views, and:

Figure 1 is a median sectional side elevation 40 of a market basket constructed in accordance with this invention;

Figure 2 is a sectional top view of a portion of the basket taken on the line 2—2 in Figure 1;

Figure 3 is a bottom view of a portion of the basket;

Figure 4 is a cross-sectional end elevation taken on the line 4—4 in Figure 2;

Figure 5 is a magnified detailed view of the 50 lower right corner of Figure 4; and,

Figure 6 is a side view of the metal strap.

Illustrated on the drawing is a market basket conventionally constructed with the exception of the basket bottom, the lower inside hoop and 55 the metal strap.

The conventional parts of the basket consist of the siding sections 10 of veneer wood which overlap at points 11, the upper outside hoop 12 with overlapping ends 13 on one side, the upper inside hoop 14 with overlapping ends 15 on the opposite side, the lower outside hoop 16 with overlapping ends 17 on one side, and the handle or bale 18 the shafts 18' of which embrace the sides of the basket as shown.

Ordinarily there is associated with a basket 10 of this class a comparatively heavy board basket bottom the thickness of which is about equal to the breadth of the lower outside hoop 16 and coplanar with the edges thereof, and ordinarily this hoop together with the siding 10 is nailed to the 15 edges of the basket bottom. Similarly the shafts of the bale 18 which overlap the hoop 16 are nailed to the edges of this basket bottom with the outside hoop and siding between them.

Instead of the aforesaid heavy or thick basket 20 bottom there is in the present invention provided a relatively very thin basket bottom 19. In fact, the basket bottom 19 is preferably made of veneer wood about double the thickness of the veneer wood siding and hoops, which latter 25 are approximately equal in thickness. This comparatively thin bottom, however, is fully adequate to support a normal basket load when seated and secured in the novel manner to be ascertained, but materially reduces the weight 30 and cost of the basket by elimination of the heavy or relatively thick conventional bottom.

The bottom 19 is marginally supported by an inside hoop 20 contiguous to the internal face of the siding 10 and having overlapping ends 21. 35 This extra internal hoop, the siding and the outside hoop 16 are all secured together by means of spaced staples 22 (called stitching in the basket trade) clenched on the inside similarly to the manner in which the upper hoops and siding are 40 united in common practice.

Athwart the basket bottom 19 on its upper face is a very thin metal strap 23 which is nailed thereto as at 24 or otherwise secured in an approved manner. This strap is provided with 45 down turned ears 25 which embrace the lateral edges of the basket bottom and are thence tucked between the inside hoop 20 and the basket siding 10.

Through the extremities of the bale shafts 18' 50 and thence in consecutive order through the outside hoop 16, the siding 10, the ears 25, and the inside hoop 20, are driven staples 26 which are subsequently clenched against the internal face of the latter hoop. In this manner the foregoing 55

parts are securely tightened and clamped together, and furthermore the basket bottom 19 is thus permanently fixed in its proper position.

As previously mentioned, the conventional basket bottom in thickness occupies the full space between the herein described bottom and the lower edges of the hoops, siding and bail shafts. Thus there was no way of clenching the nails and it was common for them to loosen and evacuate the nail holes, particularly if the wood happened to be abnormally soft. Therefore, it will be observed that as well as affording appreciable lightness and saving of lumber this improved basket by reason of the resultant provision for clenching the staples 26 is secure against loosening and opening of the parts.

There has been provided a simple and efficient device of the kind described and for the purpose specified.

20 It is obvious that minor changes may be made in the form and construction of the invention without departing from the material spirit thereof. It is not, therefore, desired to confine the invention to the exact form herein shown and 25 described, but it is desired to include all such as properly come within the scope claimed.

Having thus described the invention, what is claimed as new, is:

1. The combination with the siding and lower 30 outside hoop of a market basket, of a veneer wood lower inside hoop, a basket bottom consist-

ing of a sheet of veneer wood supported by said inside hoop, a stiffening strap athwart said bottom and secured thereto, down turned ears on the ends of said strap tucked between said inside hoop and the siding, and means securing both 5 said hoops, the siding, and said ears together.

2. The combination with the siding and shafted bail of a market basket, of a veneer wood lower inside hoop, a basket bottom consisting of a sheet of veneer wood supported by said inside hoop, a 10 stiffening strap athwart said bottom and secured thereto, ears on the ends of said strap secured to the siding and to the shafts of said bail.

3. The combination with the siding and lower 15 outside hoop of a market basket, of a veneer wood lower inside hoop, a basket bottom consisting of a sheet of veneer wood supported by said inside hoop, ear supporting members secured to said bottom, ears on said members tucked between 20 said inside hoop and the siding, and means securing both said hoops, the siding, and said ears together.

4. The combination with the siding and shafted bail of a market basket, of a veneer wood lower inside hoop, a basket bottom consisting of a sheet of veneer wood supported by said inside hoop, ear supporting members secured to said bottom, and ears on said members secured to the siding 25 and to the shafts of said bail.

30

ARTHUR HEWSON.
